(57) **CLAIM**

The ornamental design for a personal floatation device, as shown and described.

DESCRIPTION

FIG. 1 is a rear perspective view of my personal floatation device.

FIG. 2 is a front elevation view thereof.

FIG. 3 is a rear elevation view thereof.

FIG. 4 is a top elevation view thereof.

FIG. 5 is a bottom elevation view thereof; and,

FIG. 6 is a left elevation view thereof, the right elevation view being symmetrical thereto.

The broken lines form no part of the claimed design.
